UNITED STATES PATENT OFFICE.

CLEMENT G. HARRINGTON, OF MAPLEWOOD, MISSOURI, ASSIGNOR TO AMERICAN CAR & FOUNDRY COMPANY, OF ST. LOUIS, MISSOURI, A CORPORATION OF NEW JERSEY.

DOOR-OPERATING MECHANISM.

No. 892,048.

Specification of Letters Patent.

Patented June 30, 1908.

Application filed January 31, 1908. Serial No. 413,575.

To all whom it may concern:

Be it known that I, CLEMENT G. HARRINGTON, a citizen of the United States, residing at Maplewood, St. Louis county, Missouri, ⁵ have invented a certain new and useful Improvement in Door-Operating Mechanism, of which the following is a full, clear, and exact description, such as will enable others skilled in the art to which it appertains to make and ¹⁰ use the same, reference being had to the accompanying drawings, forming part of this specification, in which—

Figure 1 is a top plan view of a portion of a car provided with a door-operating mechanism constructed in accordance with my invention; Fig. 2 is a cross sectional view taken on the line 2—2 of Fig. 1; Fig. 3 is a sectional view taken on the line 3—3 of Fig. 1 looking in the direction of the arrow; Fig. 4 is an elevation of a portion of the side wall of the car; Fig. 5 is an enlarged sectional view of the device on the door to which the winding chain is attached; Fig. 6 is a detail sectional view of one of the bearing members on the door; and Fig. 7 is a detail view of one of the racks which coöperates with a pinion on the supporting shaft to cause it to move toward and away from the door.

This invention relates to dump cars, and
30 particularly to the mechanism that is em-
ployed in such cars for operating the doors in
the bottom of the car.

The main object of my present invention is to provide a door-operating mechanism of simple construction which comprises a member that is adapted to be moved underneath the door when it is closed and thus relieve the strain on the chain or cable that is used for closing the door. Other desirable features of my invention will be hereinafter pointed out.

45 Referring to the drawings which illustrate the preferred form of my invention, I designates a door arranged in the bottom or floor of the car and having one edge connected by means of hinges to a support on the underneath side of the floor. The door preferably consists of a plate provided at its edges with depending flanges that are formed by four short pieces 2 of angle iron but it will, of course, be understood that the door could be provided with integral flanges if so desired. The hinges on which the door is mounted each consists of a strap or bar of iron 3 bent 50 to form a loop or eye, as shown in Fig. 2, and

connected to the underneath side of the door by means of rivets or suitable fastening devices 4 that pass through fillers 5 arranged between the strap and the door, the angle 2 at the rear edge of the door being cut away to 60 permit said strap to project laterally beyond the edge of the door. Pins or pintles 6 pass through the eyes or loops on the door and said pintles are carried by members 6^a located beneath the floor or bottom of the car 65 and secured to the floor or to a portion of the floor framing.

A winding shaft 7 is journaled in portions of the floor framing and a chain or cable 8 is secured to said shaft and to the door to move said door into its closed position. The device on the door to which said chain or cable is connected preferably consists of an approximately hollow or box-shaped casting 9 having a narrow central L-shaped web and two integral side flanges, said device being secured to the front edge of the door and depending downwardly therefrom, as shown in Fig. 5. The vertical portion of the web of the device 9 curves inwardly at 9^a to form a recess or pocket that receives the member which retains the door in its closed position, and an opening 10 is formed in the vertical portion of said web to receive the shank of an eye-bolt 11 to which the winding chain is secured, said web being provided with a thickened portion or collar 10^a around said opening 10 to form an abutment or bearing surface for the nut 12 which retains the eye-bolt in position.

The member that is moved underneath the door after it has been closed so as to form a support for the door, consists of a shaft 13 that is rotatably mounted in elongated openings or bearings 14 formed in the center sill 95 15 of the underframing and also in a plate 16 secured to the side wall 17 of the car, as shown in Figs. 3 and 4. The openings or bearings 14 are long enough so that the shaft 13 can be moved underneath the door and 100 away from the front edge of the door to permit it to drop. The bodily movement of the shaft 13 relatively to the door is effected by means of racks 18 secured to the inside face of the plate 16 and to the center sill 15, and 105 coöoperating pinions 19 on the shaft which mesh with said racks. The end of the shaft 13 is provided with a squared portion 13^a to receive a wrench or other suitable implement for turning the shaft 13 and as the shaft 110

turns it moves bodily toward and away from the front edge of the door, the rotary movement of the shaft in one direction causing it to enter the recess or pocket in the device 9 on the door and thus forming a substantial support that takes the strain from the winding chain. I prefer to secure auxiliary bearing devices 20 to the underneath side of the door on each side of the device 9, as shown in Fig. 3, and also provide the shaft with collars 21 that coöperate with the bearings 20 when the door is closed, said bearings preferably consisting of hollow box-shaped castings, as shown in Fig. 6.

15. Retrograde movement of the winding shaft 7 is prevented by means of a ratchet 22 on the end of the shaft, and a coöoperating pawl 23 on the plate 16 and the supporting shaft 13 is also locked in position in a similar manner, said shaft being provided with a ratchet 24 that coöperates with a pivotally mounted pawl 25 on the plate 16.

Having thus described my invention, what I claim as new and desire to secure by Letters Patent is;

1. A car provided with a hinged or pivotally mounted door, mechanism for raising said door, and a shaft separate and distinct from said door-raising mechanism and arranged parallel to the front edge of the door, said shaft being adapted to be moved underneath the door to form a support therefor; substantially as described.

2. A car provided with a hinged or pivotally mounted door, means for raising said door, a shaft arranged parallel to the front edge of the door and adapted to be moved underneath same to form a support therefor, and a device on the door constructed to receive said shaft and thus retain the door in its closed position; substantially as described.

3. A car provided with a hinged or pivotally mounted door, mechanism for raising said door, a rotatable shaft separate and distinct from said door-raising mechanism and arranged parallel to the front edge of the door, and means for causing said shaft to shift bodily toward and away from the door when rotary movement is imparted thereto, the movement of the shaft in one direction carrying it underneath the door so as to form a support for same; substantially as described.

5. A car provided with a hinged or pivotally mounted door, means for raising said door, a rotatable shaft arranged parallel to the front edge of the door, means for causing said shaft to shift bodily toward and away from the door when rotary movement is imparted thereto, and a device on the underneath side of said door constructed to receive said shaft when it moves underneath the door; substantially as described.

65. 5. A car provided with a hinged or pivot-

ally mounted door, a winding shaft connected by a flexible device to the door for closing it, a shaft arranged longitudinally of the door, means for causing said shaft to move underneath the front edge of the door when it is rotated in one direction, and a device on the door provided with a recess or pocket for receiving said shaft; substantially as described.

6. A car provided with a hinged or pivotally mounted door, a winding shaft connected by a flexible device to the door for closing it, a shaft arranged longitudinally of the door, means for causing said shaft to move underneath the front edge of the door when it is rotated in one direction, a device on the door provided with a recess or pocket for receiving said shaft, and auxiliary bearing devices on the underneath side of the door which rest on said shaft when the door is closed; substantially as described.

7. A car provided with a hinged or pivotally mounted door, mechanism for closing said door, a shaft separate and distinct from said door-raising mechanism and arranged longitudinally of the door, means for causing said shaft to move underneath the front edge of the door when it is rotated in one direction, and means for locking said shaft in position for supporting the door; substantially as described.

8. A car provided with a hinged or pivotally mounted door, means for raising said door, a shaft arranged longitudinally of the front edge of the door and mounted in elongated bearings, pinions on the shaft, and stationary coöperating racks which mesh with said pinions and cause the shaft to move underneath the front edge of the door when it is rotated in one direction; substantially as described.

9. A car provided with a hinged or pivotally mounted door, means for raising said door, a shaft arranged longitudinally of the front edge of the door and mounted in elongated bearings, pinions on the shaft, stationary coöperating racks which mesh with said pinions and cause the shaft to move underneath the front edge of the door when it is rotated in one direction, and a device depending from the front edge of the door and provided with a recess or pocket for receiving said shaft; substantially as described.

10. A car provided with a hinged or pivotally mounted door, means for raising said door, a shaft arranged longitudinally of the front edge of the door and mounted in elongated bearings, pinions on the shaft, stationary coöperating racks which mesh with said pinions and cause the shaft to move underneath the front edge of the door when it is rotated in one direction, a device depending from the front edge of the door and provided with a recess or pocket for receiving said shaft, and auxiliary bearing members on the

underneath side of the door which rest on said shaft when the door is closed; substantially as described.

11. A car provided with a hinged or pivotally mounted door, a shaft arranged longitudinally of the front edge of the door and mounted in elongated bearings in the floor frame of the car, coöperating racks and pinions on said shaft and on the floor frame which cause the shaft to move toward and away from the door when it is rotated, a device depending from the door and provided with a pocket or recess for receiving the shaft when it moves underneath the door, a winding shaft, and a chain or cable connected to said shaft and to the depending device on the door; substantially as described.

12. A car provided with a hinged or pivotally mounted door, means for closing said door, a shaft arranged parallel to the front edge of the door and mounted in elongated bearings, means for causing said shaft to move underneath the door when it is rotated in one direction, a hollow casting on the underneath side of the door provided with a pocket or recess for receiving said shaft, and auxiliary bearing members adapted to rest on said shaft when the door is closed and consisting of approximately box-shaped castings; substantially as described.

13. A car provided with a hinged or pivotally mounted door, means for closing said door, a shaft arranged parallel to the front

edge of the door and mounted in elongated bearings in the floor frame and in a plate connected to the side wall of the car, racks connected to said plate and to a portion of the floor frame, pinions on said shaft which mesh with said racks so that the shaft will move underneath the front edge of the door when it is rotated in one direction, a depending device on the door provided with a recess or pocket for receiving said shaft, and means for locking said shaft to retain it in position for supporting the door; substantially as described.

14. A car provided with a hinged or pivotally mounted door, an approximately hollow box-shaped device secured to the front edge of the door and provided with a web that is disposed vertically when the door is closed, an integral collar or thickened portion surrounding an opening in said web and having a face that is inclined relatively to said web, an eye-bolt passing through said opening and retained in position by a nut which butts against the inclined face on said collar, and a chain or cable secured to said eye-bolt for operating the door; substantially as described.

In testimony whereof I hereunto affix my signature in the presence of two witnesses, this twenty ninth day of January 1908.

CLEMENT G. HARRINGTON.
